UNITED STATES PATENT OFFICE

WILLIAM H. CUTLER, OF NEWTON, MASSACHUSETTS

MOP WRINGER

Application filed January 5, 1928. Serial No. 244,641.

My invention relates to mop wringers, and more particularly aims to provide an improved and simplified device adapted to be received within and supported upon a pail, 5 bucket or the like in position to receive a mop-head and to drain liquid from the latter back into the pail or like device with which the wringer is to be used.

In the drawings, illustrating by way of example one embodiment of my invention,

Fig. 1 is a plan view of a pail or similar liquid container having a wringer embodying my invention attached thereto;

Fig. 2 is a side elevation of the wringer 15 of Fig. 1 in position upon the pail or the like, the latter being in vertical section and partly broken away;

Fig. 3 is a partial view in elevation and upon a larger scale of one attaching means 20 or clamp;

Fig. 4 is a view corresponding to Fig. 3 taken in vertical section through the wringer and pail; and

Fig. 5 is an enlarged detail view.

Referring more particularly to the drawings and first to Figs. 1 and 2 I have indicated a pail or bucket at P. The latter as illustrated is the ordinary household or galvanized metal type having a beaded upper edge or rim as indicated at R. While the device of my invention is particularly adapted for use with a pail having such beaded or otherwise thickened upper edge, it may be employed with liquid containers of other forms including wooden buckets, tubs, etc., whether or not provided with a beaded rim.

The wringer comprises a body, receptacle or cup-like device 1 preferably in the form of a truncated cone substantially as illustrated, being open at its upper and larger end and having at its smaller end a bottom 2 which desirably is flat or at least not projected downwardly beyond the side walls of the body, so that the latter may stand flat upon its own base when not in use. The wringer body may be formed of any suitable sheet material of sufficient strength such, for example, as galvanized iron or other sheet metal. It may be of various dimensions and proportions but desirably has a maximum diameter

of approximately one-half that of the pail or liquid vessel with which it is to be used, and a height not substantially exceeding one-half that of said pail or vessel, so that the wringer may be supported above and out of contact with a required quantity of liquid below it. The downward and inward inclination of the side walls of the wringer body 1 is preferably in conformity with that of the side walls of the pail with which it is to be employed.

The described wringer body or receptacle 1 is adapted to receive the absorbent head of a mop and is provided with means whereby the mop head when pressed down within the wringer or twisted within it, will have any excess liquid wrung out from it and returned to the supply in the pail. For this purpose I have illustrated a plurality of horizontal rows of vertically elongated slots 3, 3, etc., the individual slots in a given row being spaced circumferentially of the receptacle, and the slots in the respective rows arranged in staggered or intermediate relation

with respect to each other. Said slots may be of any desired form but are preferably formed with rounded ends 4 substantially as illustrated, to avoid catching or unnecessary wear upon the mop head. For similar reasons the edges 5 of the slots desirably are slightly turned outwardly as illustrated in

Fig. 5, leaving the inner surface of the receptacle entirely smooth. In the bottom wall 2 are provided the additional perforations 6, 6, etc., which also are preferably formed in a manner affording a smooth inner face at the wringer bottom.

For holding the wringer in operating position upon the pail side wall I have provided novel clamping means which as herein shown is integrally formed from a single piece of metal stock. Referring now more particularly to Figs. 3 and 4, but as also seen in Fig.

2, said means herein comprises a clamp, plate or hook-like element indicated as a whole at

7. It includes an upper or attaching portion 8 shaped to lie flatwise against the outer face of the wringer body near its top, and which is rigidly secured in said position in any

suitable manner as by means of rivets, spot welding, or otherwise, as indicated at 9, 9.

Below said attaching portion 8 the clamp is formed with an out-turned portion or shoulder 10 adapted to seat upon the upper surface of the bead or rim R of the pail. The clamp is downwardly and inwardly extended below said shoulder to form a tail or spring clamping portion 11, having its lower extremity turned slightly outwardly, as indicated at 10. 12. The described clamp is formed of a comparatively heavy, strong metal but sufficiently springy to permit the wringer body to be passed down along the inner surface of the 15 pail side wall while the clamp may be sprung down over the pail rim and along and in clamping contact with the outer face of the pail.

In order still more firmly to attach the 20 wringer to the pail the clamp is formed with a cut-out spring tongue 13, integral with the lower clamp portion at its bottom and upwardly extending therefrom. Said tongue is inturned as at 14 to provide a nub adapted 25 to press against the pail side, and above said nub the tongue 13 is reversely and outwardly curved, as at 15. The clamp proper and the tongue 13 are so proportioned and arranged 30 that as the receptacle is passed downwardly over the pail side said tongue will first be sprung outwardly by the pail rim R, but as soon as the nub 14 of the tongue has passed below said rim the tongue will snap back into engagement with the pail side, bringing its 35 out-turned portion 15 into clamping contact with the under portion of the pail rim. In this manner the clamp substantially completely encloses the pail rim, to prevent undesirable rocking movement of the wringer 40 on the pail, while said clamp also has a plurality of points of engagement with the outer face of the pail below the rim. Accordingly the wringer may be extremely firmly attached to the pail, but said attachment is effected 45 simply by downward pressure of the wringer along the pail side and without further or special manipulation of catches or other devices; but one hand of the user need be employed in so affixing the wringer. Removal 50 of the wringer is equally easy, due to the described construction, and may be accomplished by merely tilting the wringer relatively to the pail with sufficient force to cam the latch portion 15 of the tongue slightly 55 outwardly, whereupon the entire wringer may be withdrawn upwardly and freed from the pail.

It will be noted that the wringer is so proportioned and related to the pail or the like 60 with which it is to be employed that the center of the attached wringer comes within the pail bottom, a vertical line drawn through the wringer axis meeting the pail bottom at a point substantially removed from the bottom edge of the pail side wall. The pail and

attached wringer are thus well balanced and there is no tendency to upset the pail unintentionally in the process of wringing out a mop.

My invention is not limited to the particular embodiment shown and described herein, its scope being set forth in the following claims:—

1. In a mop-wringer of the twister type having a perforate mop receptacle adapted to be positioned upon and within a pail or bucket, means for readily releasably securing said receptacle in operating position comprising a metal plate fixedly attached at its upper portion to the outer face of the mop receptacle, the lower extremity of said plate being outwardly inclined to guide the pail edge up between the plate and the mop receptacle as the latter is moved downwardly along the pail side, and said plate being constructed and arranged to bear against the outer face of the pail side, said plate having an upwardly extending tongue adapted to engage beneath the pail rim firmly to position the mop receptacle but having its upper end outwardly curved whereby said tongue may be cammed outwardly by the pail rim to release it for removal of the wringer.

2. A mop wringer particularly for application to the edge of a pail having a beaded rim, said wringer comprising an open-top mop-receptacle of approximately circular cross-section and having perforate side and bottom walls, and a resilient clamping element attached on the outer face of said receptacle near its top, the lower end of said element being outwardly inclined to guide the pail rim into held engagement beneath the clamping element, and said element provided with an upwardly directed tongue for engagement beneath the pail rim, the upper extremity of said tongue being outwardly deflected for camming action with the pail rim in the release of the mop-receptacle from the pail.

In testimony whereof, I have signed my name to this specification.

WILLIAM H. CUTLER.
